UNITED STATES PATENT OFFICE.

BENJAMIN WEXLER, OF BROOKLYN, NEW YORK, ASSIGNOR TO THE PEELLE COMPANY, OF BROOKLYN, NEW YORK, A CORPORATION OF NEW YORK.

DUMB-WAITER DOOR.

1,414,387.

Specification of Letters Patent.

Patented May 2, 1922.

Application filed May 6, 1920. Serial No. 379,345.

To all whom it may concern:

Be it known that I, BENJAMIN WEXLER, a citizen of the United States, residing at the borough of Brooklyn, city of New York, county of Kings, and State of New York, have invented certain new and useful Improvements in Dumb-Waiter Doors, of which the following is a specification, reference being had therein to the accompanying drawings, which form a part thereof.

My invention relates to dumbwaiter doors, and more particularly to a fireproof structure of this type.

The main object of the invention is to provide a dumbwaiter door structure wherein the door and its frame at the door opening is so constructed as to be capable of installation as a unit in the masonry of the dumbwaiter shaft, thus avoiding any necessity for fitting or assembling the various elements entering into the door structure by mechanics during the erection of the building, and at the same time ensuring a fixed permanent relation of parts which will ensure a free easy movement of the door panels in opening and closing same after the completion of the installation.

The frame which is composed entirely of metal so as to be fireproof, not only includes therein suitable guides or tracks for a movable door which preferably is of the multiple section, counterbalanced or semi-automatic type, but also cross braces forming that portion of the sill and lintel of the shaft opening adjacent the door.

The side bars and the cross braces are so constructed as to close any gaps about the shaft opening, thus forming a metal barrier about this opening which will prevent the passage of smoke or flames between the frame and the masonry wall, and at the same time lend rigidity and strength to the entire door structure.

To prevent possibility of the displacement of the frame, I preferably provide the side bars thereof with suitable anchors adapted to be imbedded in the masonry wall, thus making the frame substantially integral with the wall.

In order to include a factor of safety in the operation of the device, I provide one of the side bars of the frame at a point where it will be accessible from the floor side of a shaft, with a hand-operated locking mechanism which will lock the doors when they

are in either the opened or the closed position.

The doors themselves are so constructed and combined in relation to the metal frame, that they will expose substantially the entire area of the door opening when the door is opened and yet will have the opening movement thereof so limited as to preclude any possibility of the user imparting such a movement to the door structure as will interfere with access thereto when it is desired to close the door.

The invention consists primarily in a dumbwaiter door embodying therein metal side bars, guides or tracks carried by said bars respectively, cross braces carried by said bars, said braces being spaced apart a distance equaling the height of a shaft opening, a vertically movable door structure mounted upon said guides or tracks and adapted to close the space within said side bars and said cross braces, pulleys above the upper of said cross braces, and a suspension cable co-operating with said door structure and said pulleys; and in such other novel features of construction and combination of parts as are hereinafter set forth and described, and more particularly pointed out in the claims hereto appended.

Referring to the drawings,

Fig. 1 is an elevation of a dumbwaiter door embodying my invention, from the shaft side thereof;

Fig. 2 is a vertical section therethrough;

Fig. 3 is a horizontal section at approximately the meeting point of the two door sections; and

Fig. 4 is an isometric view of the door structure with the door panels removed therefrom.

Like letters refer to like parts throughout the several views.

In the embodiment of the invention shown in the drawings, *a* and *b* indicate two vertically extending side bars formed of angle iron, one flange *a'*—*b'* of each bar being adapted to extend parallel with the wall of the shaft, and the other flange *a''*—*b''* being adapted to form part of the opposite jambs of the shaft opening adjacent the wall of said shaft.

The flanges *a'*—*b'* have riveted, bolted, or otherwise secured thereto, vertically extending tracks or guides preferably formed of flat metal strips *c*—*d* extending parallel

- with said flanges and spaced away therefrom the desired distance by means of the vertically extending bars $c'-d'$ disposed between said strips and the said flanges.
- 5 The guides or tracks are preferably shorter than the side bars. It will be observed by the construction of track described, no gaps are presented adjacent the flanges $a'-b'$, through which smoke or flame might pass.
- 10 To facilitate the mounting of the frame in relation to the masonry wall, I preferably employ angular anchors e adapted to be imbedded in the masonry about the shaft opening, a construction which especially adapts the door structure to be used in buildings during erection, although if it be desired to install this structure in a completed building without disturbing the wall adjacent the shaft, the flanges $a'-b'$ may be utilized to secure the entire frame in position by any of the well known expedients known in the fireproof elevator door art.
- 20 Connecting the side bars $a-b$ are cross braces $f-g$ preferably formed of angle iron secured to the flanges a^2-b^2 of the side bars by means of angle brackets h and i . The cross braces in addition to acting as stays for imparting the desired rigidity to the structure of the frame, also form a part of the lintel and sill of the shaft opening and form a barrier to fire and smoke at the top and the bottom of the shaft opening. The brace f in addition to this, supports that part of the masonry of the wall above same.
- 25 The flanges f' and g' of the cross braces f and g are in the same vertical plane as the flanges a' and b' of the side bars, while the flanges f^2-g^2 occupy parallel horizontal planes, said braces being spaced apart a distance coinciding with the height of the door opening.
- 30 Adjacent the upper end of the bars $a-b$ is a cross bar j having a pulley or sheave box $j'-j^2$ formed at each end thereof, preferably by bending the ends of this bar to form, and riveting the bent end to the bar. Mounted in the boxes $j'-j^2$ are the pulleys or sheaves $k-k'$.
- 35 Closing the space within the side bars $a-b$ and the cross braces $f-g$ is a door structure which, in the form of the invention shown, consists of two vertically movable sections $m-n$ connected by suitable suspension means, as the chains $o-o'$ passing over the pulleys $k-k'$ respectively. One end of each of said chains is connected to the top rail of the frame of the upper door m and the other end of each of said chains is connected to hanger clips n' secured to the opposite side rails of the lower door section n .
- 40 The upper door section m has upon the bottom rail thereof, an astragal m' of a width to enter the door opening between the side bars a and b and thus serve the two-fold function of closing any gap at the parting of the two door sections and limiting the extent of the opening movement of the door sections by engagement with the cross brace f . This astragal is also utilized as a part of the locking means to hold the doors in their opened or closed position.
- 45 The door sections m and n may be of any desired or approved fireproof structure, these sections in the form of the invention shown, being composed of an angle iron frame m^2-n^2 supporting a sheet metal panel m^3-n^3 . The opposite side bars of the frame m^2 and n^2 each have permanently secured thereto an angle bar $p-p'$, one flange of which is adapted to enter and have movement in the space between the plates c and d of the guides or tracks and the flanges $a'-b'$ of the side bars respectively.
- 50 Carried by one of the flanges a^2-b^2 of the side bar a or b so as to be exposed upon the floor side of the frame structure, is a manually operative locking mechanism adapted to co-operate with the astragal m' , and either hold the door in the opened or the closed position, as the case may be. This mechanism in the form of the invention shown in the drawings, consists of an oscillatory lever q pivoted adjacent the lower end thereof and having adjacent the top thereof a projecting stop q' having a downwardly presented bevelled portion, and intermediate the ends thereof, a projecting stop q^2 having an upwardly presented bevelled portion. Said stops are carried by the long arm of said lever, the short arm thereof having a projecting heel q^3 adapted to engage a stop r carried by the side bar.
- 55 Acting upon the lever q is a spring s having a normal tendency to hold the heel q^3 against the stop r and project the bevelled portions of the stops $q'-q^2$ in the path of movement of the astragal m' .
- 60 The lever q is pivotally mounted upon a plate t permanently secured to one of the side bars as a' , which plate has a segmental opening t' therein adapted to receive a pin q^4 carried by said lever. Secured to the lever q is a hand-hold u by means of which said lever may be oscillated against the tension of the spring s .
- 65 The operation and advantages of the herein described dumbwaiter door are substantially as follows:—
- 70 A dumbwaiter door made in accordance with my invention is completely assembled in the shop, the side bars $a-b$, cross braces $f-g$ and cross strip j all being cut to the proper dimensions and permanently united under conditions which ensure the desired accuracy in the relation of the several parts and ease of operation of the doors. If desired, the doors may be assembled in the structure at the shop so that the assembling

of the structure in a building under erection, forms a part of the masonry construction and require no special mechanics to install the door equipment.

5 Of course, if desired, the shaft opening closed by the doors may be finished with any desired trim, this, however, having no relation to my invention.

When the door structure is installed in the 10 building, the flanges $a'-a^2$, $b'-b^2$, $f'-f^2$ and $g'-g^2$ form a noninflammable barrier about the shaft opening, the frames m^2-n^2 being held sufficiently close to the flanges $a'-b'$ by the rails or guides $c-d$ and by the 15 angle bars $p-p'$, to leave no gaps of sufficient width to permit smoke or flame to pass about the door sections m and n to within a room from the dumbwaiter shaft.

By employing a multiple section door of 20 the counterbalanced or the semi-automatic type, ease of operation of the door is secured, and compactness in the dumb-waiter installation is possible.

When the door is closed, the spring s will 25 hold the lever q in position with the stop q' in engagement with the top of the astragal m' . To open a door it is necessary to use the hand-hold u to draw the upper arm of the lever q outwardly and disengage this stop 30 from the astragal.

When the stop is thus disengaged, the upper door section may be raised by pressure applied to the astragal, it being possible to release the lever immediately following the initial movement of the door.

The opening movement of the door sections will be limited by the engagement of the astragal m' with the flange f^2 at the lintel of the shaft opening, the engagement of 40 the astragal with the bevel of the stop q' actuating the lock mechanism so as to hold the door in the opened position.

To permit the closing of the door, it is necessary to use the hand-hold u to retract 45 the stop q' from its operative relation to the astragal m' .

When doors of the counterbalanced type are used, the astragal is always accessible to facilitate the closing of the doors, which is 50 also true if a self-opening type of semi-automatic door is used. If, however, a self-closing door of the automatic type is used, it is necessary to use the astragal only to open the doors.

55 It is not my intention to limit the invention to the precise details of construction shown in the accompanying drawings, it being apparent that such may be varied without departing from the spirit and scope of 60 the invention.

Having described the invention, what I claim as new and desire to have protected by Letters Patent, is:-

1. A dumbwaiter door embodying therein 65 metal side bars, guides or tracks carried by

said bars respectively, cross braces carried by said bars, said braces being spaced apart a distance equaling the height of a shaft opening, a vertically movable door structure mounted upon said guides or tracks and 70 adapted to close the space within said side bars and said cross braces, pulleys above the upper of said cross braces, and a suspension cable co-operating with said door structure and said pulleys.

2. A dumbwaiter door embodying therein vertically extending metal angle bars each having one flange adapted to extend parallel with the wall of a dumbwaiter shaft, and a flange adapted to form a side jamb of an 80 opening in said shaft, guides or tracks carried by said first named flange in the shaft, cross braces carried by said last named flanges and spaced apart a distance equaling the height of a shaft opening, a vertically 85 movable door structure mounted upon said guides or tracks and adapted to close the space within said side bars and said cross braces, pulleys above the upper of said cross braces, and a suspension cable co-operating 90 with said door structure and said pulleys.

3. A dumbwaiter door embodying therein vertically extending metal angle bars each having one flange adapted to extend parallel with the wall of a dumbwaiter shaft, and 95 a flange adapted to form a side jamb of an opening in said shaft, guides or tracks carried by said first named flange in the shaft, angle iron braces carried by said last named flanges, one flange of each of said braces 100 being substantially flush with the first named flange of said vertical angle bars, and the other flanges of said braces being parallel and spaced apart a distance equaling the height of said shaft opening and forming the lintel and sill of said opening, a vertically movable door structure mounted upon said guides or tracks and adapted to close the space within said side bars and 105 said cross braces, pulleys above the upper of said cross braces, and a suspension cable co-operating with said door structure and said pulleys.

4. A dumbwaiter door embodying therein vertically extending metal angle bars each 110 having one flange adapted to extend parallel with the wall of a dumbwaiter shaft, and a flange adapted to form a side jamb of an opening in said shaft, anchors projecting from said last named flanges and adapted 115 to be imbedded in the masonry of a wall, guides or tracks carried by said first named flange in the shaft, cross braces carried by said last named flanges and spaced apart a distance equaling the height of a shaft opening, a 120 vertically movable door structure mounted upon said guides or tracks and adapted to close the space within said side bars and said cross braces, pulleys above the upper 125 of said cross braces, and a suspension cable 130

- 41 co-operating with said door structure and said pulleys.
5. A dumbwaiter door embodying therein metal side bars, guides or tracks carried by said bars respectively, cross braces carried by said bars, said braces being spaced apart a distance equaling the height of a shaft opening, two vertically and oppositely movable door sections mounted upon said guides or tracks and adapted together to close the space within said side bars and said cross braces, pulleys above the upper of said cross braces, hanger clips carried by the lower of said sections, suspension cables secured to the opposite sides of the top of the upper of said sections and to said clips, and passing about said pulleys, and a locking lever having a plurality of stops thereon adapted to co-operate with one of said door sections and retain said section in either the opened or the closed position.
6. A dumbwaiter door embodying therein metal side bars, guides or tracks carried by said bars respectively, cross braces carried by said bars, said braces being spaced apart a distance equaling the height of a shaft opening, two vertically and oppositely movable door sections mounted upon said guides or tracks and adapted together to close the space within said side bars and said cross braces, an astragal carried by the upper of said sections and projecting within said shaft opening, pulleys above the upper of said cross braces, hanger clips carried by the lower of said sections, a suspension cable secured to the opposite sides of the top of the upper of said sections and to said clips respectively, and passing about said pulleys, and a locking lever pivotally mounted upon one of said side bars and having a stop at the top thereof adapted to engage the bottom of the astragal when the door is opened, and a second stop thereon adapted to engage the top of said astragal when the door is closed, whereby said door will be locked in either the opened or the closed position.
7. A dumbwaiter door embodying therein vertically extending metal angle bars each having one flange adapted to extend parallel with the wall of a dumbwaiter shaft, and a flange adapted to form a side jamb of an opening in said shaft, guides or tracks formed of flat metal strips extending parallel with said first named flanges respectively, bars disposed between a portion of said strips and adapted to space them away from the flange supporting same, cross braces carried by said last named flanges and spaced apart a distance equaling the height of a shaft opening, a vertically movable door structure mounted upon said guides or tracks and adapted to close the space within said side bars and said cross braces, pulleys above the upper of said cross braces, and a suspension cable co-operating with said door structure and said pulleys.
8. A dumbwaiter door embodying therein vertically extending metal angle bars each having one flange adapted to extend parallel with the wall of a dumbwaiter shaft, and a flange adapted to form a side jamb of an opening in said shaft, guides or tracks formed of flat metal strips extending parallel with said first named flanges respectively, bars disposed between a portion of said strips and adapted to space them away from the flange supporting same, cross braces carried by said last named flanges and spaced apart a distance equaling the height of a shaft opening, a vertically movable door structure having an angular metal frame, the opposite side bars of said frame each having an angle bar permanently secured thereto, one flange of which is adapted to enter the space between said strip and the angle supporting same, said door structure being adapted to close the space within said side bars and said cross braces, pulleys above the upper of said cross braces, and a suspension cable co-operating with said door structure and said pulleys.
9. A dumbwaiter door embodying therein metal side bars, guides or tracks carried by said bars respectively, cross braces carried by said bars, said braces being spaced apart a distance equaling the height of a shaft opening, a vertically movable door structure mounted upon said guides or tracks and adapted to close the space within said side bars and said cross braces, a cross bar secured adjacent the top of said side bars, pulley boxes formed at each end thereof, a pulley mounted in each of said boxes, and a suspension cable co-operating with said door structure and said pulleys.

In witness whereof I have hereunto affixed my signature, in the presence of two subscribing witnesses, this 5th day of May, 1920.

BENJAMIN WEXLER.
